TOBACCO DISPENSER

Herman E. Anderson, De Ridder, La., assignor to Eldridge L. Morris, De Ridder, La.

Application December 8, 1947, Serial No. 143,025

Term of patent 7 years

(Cl. D85—7)

To all whom it may concern:

Be it known that I, Herman E. Anderson, a citizen of the United States of America, residing at De Ridder, Beauregard Parish, State of Louisiana, have invented a new, original, and ornamental Design for a Tobacco Dispenser, of which the following is a specification, reference being made to the accompanying drawing, forming a part thereof.

Fig. 1 is a front view of a tobacco dispenser showing my new design;

Fig. 2 is a side view thereof; and

Fig. 3 is a top plan view thereof.

I claim:

The ornamental design for a tobacco dispenser substantially as shown.

HERMAN E. ANDERSON.
